UNITED STATES PATENT OFFICE

CLEMENTS BATCHELLER, OF PORTSMOUTH, NEW HAMPSHIRE, ASSIGNOR TO BEMIS INDUSTRIES, INCORPORATED, OF BOSTON, MASSACHUSETTS, A CORPORATION OF DELAWARE

ROOFING STARTER

Application filed January 24, 1929. Serial No. 334,845.

This invention relates to roofing and in particular to a way of making what is known as a starter for use in the marginal course of a shingled roof.

5 The primary object of the invention is to economize in time and in material in the manufacture of roofing starters and to make it easier to ship them and to prepare them, on the job, for the roofing operations.

10 A preferred embodiment of the invention is described hereinafter and reference is made, in the course of the description, to the diagrams in the accompanying drawings.

15 In the drawings—

Figure 1 is a diagrammatic plan view of a hexagonal shingle.

Figure 2 is a diagrammatic plan view of a starter corresponding to the shingle shown 20 in Figure 1.

Figure 3 is a diagrammatic plan view of a type of honeycomb shingle corresponding to the starter of Figure 2.

Figure 4 is a diagrammatic plan view of 25 a portion of a shingled roof near the eaves showing the relation of the starter course to the main shingle courses.

Figure 5 is a diagrammatic plan view of 30 a shingle blank showing one way in which starter sections are formed.

Figure 6 is a diagrammatic plan view of a honeycomb shingle showing the way in which a starter is formed therefrom.

Figure 7 is a diagrammatic plan view of 35 a starter blank showing how the starter sections are formed from it according to the present invention.

Figure 8 is a diagrammatic sectional view 40 through a blank, such as that shown in Figure 7, at right angles to the diagonal groove.

In covering roofs with rigid shingles of the hexagonal or the honeycomb type it is the common practice to use what is termed a starter. This is a section resembling a 45 part of the shingle with which it is used. The starters are placed side by side along the eaves to form a course which presents one edge parallel to the eaves and, which, at its other edge, is like a shingle course. 50 The succeeding course which is of shingles

therefore can be laid on the upper parts of the starters in the same manner as if they were shingles.

When the shingles are of the types shown 55 in Figures 1 and 3 having truncated corners forming flat sides 10 which abut with like sides on the adjacent shingles of a course, it is not possible to form corresponding starters by dividing a shingle on a central line. The starters 11 as shown in Figures 2 and 4 have flat abutting sides 12 similar to the sides 10 on the shingles. The shape of a starter for use with shingles of the types shown in Figures 1 and 3 is shown in Figure 2 and the relation of the starters 60 to the shingle courses may be observed in Figure 4. It is evident that there must be a correlation between the size of the starter and that of the shingle, in that the width of the butt portion 13 of a starter must be 65 equal to the width of the rectangular midportion 14 of a shingle.

Starters commonly have been made in two ways, either by cutting a shingle blank into two starters of unequal size or by cutting off 70 the lower part of a shingle. As indicated by the dotted lines in Figure 5, a shingle blank from which a shingle such as that of Figure 1 may be formed by removing the corners beyond the dotted lines 15, may be 75 cut along the lines 15, 16 and 17 to give two starters of different sizes which we may term A and B. The size A starter may be used with shingles cut from the same size blank since both the A starter and the shingle then have the same width of butt as indicated respectively by the dimension X in Figure 5. The starter B can be used only 80 with shingles cut from a smaller blank. The difficulty arises from the fact that while different sizes of shingles are used they are not used to the same extent. If more large shingles are used than small ones, a number 85 of B starters would be produced beyond the demand for them since everytime an A starter is made, a B starter can not be avoided.

The above assumes that the starters are 90 made at the factory and there is therefore inherent in the method the need of shipping them to the job. The problem of packing 100

the starters is more difficult than of packing shingles, the latter being substantially square, and the result is a loss due to breakage in transit.

5 It is a common practice, as a preferable alternative to the above described method, to make the starters at the job. The builder has a portable shear and he forms what starters he needs by cutting the lower end 10 off a number of shingles, that is, by cutting along the line 18 in Figure 6.

The present invention has as its underlying thought the formation of two starters of equal size from an oversize blank 20 (vide Fig. 7), which is larger than the blank from which the corresponding shingle is cut. As shown in Figure 7, the blank 20 is of such size that if it is divided along a diagonal 21 and then truncated by cutting 20 along the lines 22 crossing the same diagonal, two equal size starters are formed each having a butt of width X. Such starters correspond to and are to be used with shingles cut from a blank such as that 25 shown in Figure 5 which is smaller than the blank 20 and gives a shingle of width X. To form a B starter, a blank smaller than blank 20 would be used but nevertheless larger than the blank from which are 30 cut the shingles corresponding to the B starters. So with other sizes.

By an oversize blank, I therefore mean one whose size is greater than that of the blank used for a corresponding shingle, and 35 by a corresponding shingle I mean one which has the same width X as the starter so that the corresponding starter and shingle may be used on the same roof.

It is possible to form the starters from 40 the oversize blanks at the factory but to facilitate the packing of them and to make possible a more rugged packing with consequent less breakage in transit, I provide a way of retaining the substantially square 45 shape for shipment without making it necessary to do any cutting operation requiring expensive tools at the job.

The material which I prefer for such rigid roofing sections as are concerned here 50 is the well known cement-fibre, generally cement asbestos, sheet which is formed from a plastic mass by a pressing operation. While the starter blanks are being pressed and still are plastic, I put a V-groove in 55 one surface of each blank along a diagonal. Then the corners are cut off by the same machines that are used for truncating the shingle blanks and the blanks thus grooved are shipped. At the job it is a matter of no 60 difficulty to break the blank into two starters because of the definitely located weakened portion along the line of desired fracture. If desired the truncation may be done at the 65 job as the relative order of doing these operations is not material, the only limita-

tion being, of course, that where the grooving step is included, it must precede the dividing of the blank into starters.

The preferred way of forming the V-groove is to do so in the course of pressing 70 the still plastic sheets which are to become the rigid blanks. The pressing commonly is done by placing the sheets on steel plates which are piled up in a press. I provide a separate thin piece of metal on one side of each plate. This piece of metal is flat except for a V-boss extending diagonally across one face. As the sheets and press plates are piled up and compressed, each plate having a thin V-bossed piece associated with it, a diagonal groove is formed 80 in each sheet resulting in a starter blank with a properly located easily frangible portion.

This method of making starters eliminates 85 much of the waste material thought to be unavoidable with the methods in use. It also brings about an economy of time, reduces the loss in shipment and simplifies the work of the builder.

I wish to include within the scope of protection given me all such variations from the method described as come within the fair meaning of the following claims.

I claim—

1. The method of making roofing starters for use with corresponding honeycomb or hexagonal shingles having abutting sides which comprises dividing an oversize blank into two starters of width equal to that of 100 the corresponding shingles.

2. The method of making roofing starters for use with corresponding honeycomb or hexagonal shingles which comprises truncating two corners of a substantially square oversize blank and dividing the blank along the diagonal connecting said corners to give two starters, the truncations being at such a distance from the corners that the width of the starters will be equal to that of the 110 corresponding shingles.

3. The method of making roofing starters for use with corresponding honeycomb or hexagonal shingles which comprises truncating two corners of a substantially square 115 oversize blank, weakening said blank along the diagonal connecting said corners and subsequently dividing the blank at the weakened portion.

4. The method of making roofing starters for use with corresponding honeycomb or hexagonal shingles which comprises weakening a substantially square oversize blank along one diagonal, subsequently dividing the blank at the weakened portion and, at 125 some point in the sequence of operations, truncating the corners of said blank to give a starter width equal to that of the corresponding shingles.

5. The method of making roofing starters 130

for use with corresponding honeycomb or hexagonal shingles, the starters being made of a cement-fibre composition pressed while a plastic mass, which comprises forming a groove along one diagonal of a substantially 5 square oversize blank while the blank still is plastic, to form an easily frangible portion, truncating the corners of the blank at the ends of said diagonal at such distances in from the corners that the width of the 10 starter will be equal to that of the corresponding shingles, and subsequently dividing the blank at the said groove.

6. The method of making roofing starters for use with corresponding honeycomb or 15 hexagonal shingles, the starters being made of a cement-fibre composition pressed while a plastic mass, which comprises forming, in the course of the pressing operation, a groove along one diagonal of a substantially 20 square oversize blank while the blank still is plastic, to form an easily frangible portion, truncating the corners of the blank at the ends of said diagonal at such distances in from the corners that the width between 25 the truncations is equal to the width of the corresponding shingle, and subsequently dividing the blank at the said groove.

7. In the manufacture of roofing starters for use with corresponding hexagonal or 30 honeycomb shingles, the step of forming a weakened portion along one diagonal of an oversize blank.

8. An oversize roofing blank having a 35 weakened portion along one diagonal.

9. An oversize blank having a weakened portion along one diagonal and truncated corners at the ends of said diagonal giving a width equal to that of a corresponding shingle.

40 In testimony whereof I have signed my name to this specification.

CLEMENTS BATCHELLER.
